UNITED STATES PATENT OFFICE.

EUGENE G. FALCONER, OF SAN FRANCISCO, CALIFORNIA.

DESIGN FOR A COMBINED KEY-RING AND BOTTLE-OPENER.

46,468.

Specification for Design.

Patented Sept. 29, 1914.

Application filed July 30, 1914. Serial No. 854,890. Term of patent 7 years.

To all whom it may concern:

Be it known that I, EUGENE G. FALCONER, a citizen of the United States, residing in the city and county of San Francisco and State of California, have invented a new, original, and ornamental Design for a Combined Key-Ring and Bottle-Opener, of which the following is a specification, reference being had to the accompanying drawings, forming a part thereof.

Figure 1 is a plan view of a combined key

ring and bottle opener, showing my new design. Fig. 2 is a side elevation showing the comparative thickness of combined key ring and bottle opener.

I claim:

The ornamental design for a combined key ring and bottle opener, as shown.

EUGENE G. FALCONER.
